UNITED STATES PATENT OFFICE.

AXEL S. VOGT, OF ALTOONA, PENNSYLVANIA.

ENGINE CROSS-HEAD.

SPECIFICATION forming part of Letters Patent No. 450,830, dated April 21, 1891.

Application filed April 21, 1890. Serial No. 348,799. (No model.)

To all whom it may concern:

Be it known that I, AXEL S. VOGT, a subject of the King of Sweden, and a resident of Altoona, county of Blair, State of Pennsylvania, have invented a certain new and useful Improvement in Guides for Engine Cross-Heads, of which the following is a true and exact description, reference being had to the accompanying drawings, which form a part of this specification.

My invention relates to the devices used for guiding the cross-head of an engine, and particularly the guides for locomotive cross-heads, the object being to improve the construction of such guides, making them at the same time more simple and stronger than has heretofore generally been the case.

The nature of my improvement will be best understood as described in connection with the drawings in which it is illustrated, and the novel features which I desire to protect by Letters Patent are hereinafter clearly set forth in the claims.

Reference being now had to the drawings which illustrate my invention, Figure 1 is an elevation showing my improved cross-head guide, together with the parts of a locomotive-engine to which it is attached, and the cross-head moving in said guide. Fig. 2 is a plan view of the cross-head guide. Fig. 3 is a cross-sectional view on the line $x-x$ of Fig. 1. Fig. 4 is a cross-sectional view on the line $z-z$ of Fig. 1. Fig. 5 is a plan view of the cross-head. Fig. 6 is a side elevation of the cross-head on the section-line $w-w$ of Fig. 5, and Fig. 7 is a view showing a modification of my improved cross-head guide.

A indicates the end of the locomotive-cylinder.

B is a part of the frame of the locomotive known as the "yoke."

C is the piston-rod.

D is the cross-head, d being a socket to receive the end of the piston-rod C, and d' a bearing formed in the cross-head to receive the pin of the connecting-rod. d^2 is the guiding portion of the cross-head, d^3 a shoe or slipper secured to the upper face of the guiding portion d^2 , and d^4 similar slippers or shoes secured to the lower faces of the guiding portion of the cross-head.

E is the cross-head guide, which I make, as shown, of two L-shaped sections E' E', the long arms $e e$ of which are abutted against each other and secured together by bolts F F, &c. These sections E' consist, essentially, of the long arms $e e$, the downwardly-extending portions $e' e'$, and the inwardly-extending ends $e^2 e^2$, which extend toward each other, their inner surface being horizontal and parallel to the inner surface of the long arms $e e$. These parallel surfaces form the guiding-surfaces against the slippers $d^3 d^4 d'$ of the cross-head rest, the portion d^2 of the cross-head and the standard connecting it with the cross-head proper being inclosed in the T-shaped recess formed between the sections E' E'.

In order to strengthen the cross-head guide, I form on the outer portion of the long arms $e e$ a strengthening-rib e^3 . Preferably the rib is formed at the inner extremity of the arm e , so that when the two sections E' are secured together the ribs will also abut against each other, as shown in Figs. 1 to 4; but the strengthening-ribs e^3 may be formed on any portion of the long arms e , and in Fig. 7 I have shown them as formed at the outer extremity of the arms.

Having now described my invention, what I claim as new, and desire to protect by Letters Patent, is—

1. A cross-head guide E, consisting of two L-shaped sections E' E', secured together with their long arms abutting against each other, as described, and so as to form a T-shaped recess to receive the guiding portion of the cross-head and afford bearings for its upper and lower bearing-surfaces.

2. A cross-head guide E, consisting of two L-shaped sections E' E', having bearing-ribs e^3 formed on the outside of their long arms, said sections being secured together with their long arms abutting against each other, as described, and so as to form a T-shaped recess to receive the guiding portion of a cross-head and afford bearings for its upper and lower bearing-surfaces.

A. S. VOGT.
